CLAIM

We claim the ornamental design for a monitoring camera, as shown and described.

DESCRIPTION

FIG. 1 is a top, front, right perspective view of a monitoring camera in accordance with our design;

FIG. 2 is a top plan view thereof;

FIG. 3 is a front elevational view thereof;

FIG. 4 is a left side elevational view thereof;

FIG. 5 is a right side elevational view thereof;

FIG. 6 is a bottom plan view thereof; and,

FIG. 7 is a rear elevational view thereof.

The broken lines shown in the drawings depict portions of the monitoring camera that form no part of the claim design.
